SAFETY RAZOR BLADE HOLDER

Aaron Richstone, Poughkeepsie, N. Y.

Application February 24, 1938, Serial No. 192,274

1 Claim. (Cl. 30—333)

This invention relates to a safety razor blade holding device.

The object of this invention is to provide a holder for a standard form of double edged razor blade, the holder being so constructed that the blade may quickly and readily be attached thereto and removed therefrom, the blade being so held on the holder whereby the device may be used for shaving by one who shaves with a straight razor in order to thus dispense with the troublesome honing required in the use of a straight razor necessitating skill and the expenditure of time.

Other objects of the invention relate to the safety blade holder device being adaptable for use for stropping razor blades, as a utility knife in the home, office or shop, and for a multitude of other purposes.

Important objects of the invention are thus to provide a holder of the character described, which will accurately and rigidly dispose of the blade at the proper angle on the holder for shaving or stropping purposes, and which blade is releasably held in position by a spring backing plate, the whole device embodying but two parts in addition to the razor blade, which may be effectively operated even by unskilled persons, and which may be conveniently and quickly operated to secure a blade or to release the latter therefrom.

In the accompanying drawing in which similar and corresponding parts are designated by the same characters of reference throughout the several views in which they appear:—

Figure 1 is a side view of the safety razor blade holder constructed in accordance with the present invention.

Figure 2 is a front edge elevational view of the same.

Figure 3 is a separated view showing the safety razor blade mounting portion of the holder and the spring backing plate in position prior to assembly of the same on said holder.

Referring in detail to the drawing, 10 denotes the safety razor blade holder comprising a handle 11, and a fixed clamping jaw 12 formed integral therewith at one end thereof, the entire holder 10 being preferably formed of metal of any desired finish and character. The fixed clamping jaw 12 is made slightly wider than the width of the handle 11 as shown and is provided with a depressed flat jaw surface 13 having at each end thereof a shoulder 14. The distance between the shoulders 14 is such as to be equal to the length of a standard form of double edge

razor blade 15 shown, see Figure 3, seated on the jaw surface 13, with the transverse edges thereof engaging the shoulders 14.

Formed integral with the jaw 12 or otherwise fixed thereto are a pair of longitudinally spaced centering pins 16 arranged to one side of the center longitudinal plane of the jaw 12 and projecting above the jaw surface 13. The size of the pins 16 are such as to snugly fit within the conventional centering openings in the razor blade 15 whereby to properly position the same on the jaw 12. It will be noted that the position of the pins 16 on the jaw 12 is such that with the razor blade 15 centered thereby, only one edge portion 15a of the razor blade 15 will project beyond, what is the forward edge 12a of the jaw 12, as clearly shown in Figure 3, the other edge 15b of the razor blade 15 lying flush with the back edge 12b of the jaw 12 so as to be completely covered thereby.

The opposed sides of the pins 16 are each notched or grooved as at 17 for a purpose to be hereinafter described.

In order to lock the razor blade 15 to the holder 10 there is provided a removable clamping jaw 18 formed to provide a spring backing plate. The removable clamping jaw 18 is formed of spring steel, of a length and width slightly less than the length and width of the razor blade 15. At one long edge of the removable clamping jaw 18 there is formed a pair of longitudinally spaced re-entrant cut-away portions 19 to define a central tongue 20 having parallel transverse edges 21, the portions adjacent to each edge 21 being curved upwardly as at 22 to provide a spring bow. The length of the tongue 20 or spring bow from the transverse edge 21 to transverse edge 21 is equal to the distance between the opposed bases of the grooves 17 in the pins 16.

The width of the cut-away portions 19 is such as to receive therein the solid portions of the pins 16, in the assembly of the removable clamping jaw 18 with the fixed jaw 12, the bottoms of said cut-away portions 19 being curved as at 23 to provide limiting stops for inward movement of said jaw 18.

Thus with a razor blade 15 positioned on the fixed clamping jaw 12, see Fig. 3, the same is clamped thereto by the removable spring clamping jaw 18 which is assembled by inserting the tongue 20 with its upwardly curved ends 22 into the grooves 17 of the pins 16. The curvature of said curved ends 22 is such that the same will react against the heads 16a of the pins 16, see Figure 2 to set up a spring pressure in the body of

the removable clamping jaw 18 to tightly press the same against the razor blade 15 thus maintaining the same resiliently clamped to the fixed jaw 12 in the manner readily apparent. The 5 width of the removable jaw 18 is such as to co-act with the edge 12b of the fixed jaw 12 to completely enclose the edge 15b of the razor blade as shown in Figure 1.

It will thus be seen that an extremely simple 10 and efficient holder for a safety razor blade has been provided. It is to be understood, however, that the showing thereof is merely illustrative of the embodiment of the invention, and that the actual needs of manufacture and practice 15 may necessitate certain mechanical variations. It is therefore, not intended to limit the invention to the disclosure thereto herein illustrated, but rather to define such limitations in the claim hereunto appended.

20 Having thus described my invention, I claim as new and desire to secure by Letters Patent:

In combination, a safety razor blade holder comprising a handle, a fixed clamping jaw formed integral with one end of said handle, a depressed 25 rectangular flat clamping surface formed on one side of said fixed clamping jaw extending the full width thereof and defining at each end a trans-

verse shoulder disposed in parallel relation to each other, a pair of longitudinally spaced pins arranged to one side of the longitudinal center line of said clamping surface and normal thereto, each pin having a flat side and an overhanging head disposed in opposed relation to each other and with said flat sides parallel to said shoulders, said pins and shoulders acting to center and hold a safety razor blade against movement in any direction on said clamping surface except transverse movement in one direction and so positioning said blade that only one edge thereof will extend beyond the longitudinal edge of said clamping jaw nearest to said pins, and a removable clamping jaw rectangular in shape of the same 15 width as said clamping surface but of less length thereof comprising an intermediate tongue defined by a pair of longitudinally spaced transverse slots extending inwardly from one longitudinal edge thereof, each transverse end of said tongue being bowed upwardly to provide a resilient holding portion, said slots being adapted to slidably receive said pins and said resilient holding portions engaging the underside of the heads of said pins whereby to securely clamp 25 said blade to said holder.

AARON RICHSTONE.
